MUFFLE PLATE

Robert Kirkpatrick, Worcester, Mass., assignor to
 Norton Company, Worcester, Mass., a corpora-
 tion of Massachusetts

Application March 5, 1936, Serial No. 67,338

1 Claim. (Cl. 263—42)

The invention relates to muffle furnaces and to muffle plates therefor, and with regard to its more specific features to plates for that type of furnace known as the Manion furnace.

One object of the invention is to provide an improved muffle plate which will transmit an increased amount of heat. Another object of the invention is to provide a construction for a bottom plate for a furnace of the type indicated of high heat conducting qualities yet adequate strength. Another object of the invention is to provide a construction of the type indicated in which the ratio of conductance to strength is high. Another object of the invention is to improve the furnace described in United States Letters Patent to Leo W. Manion No. 1,607,681. Another object of the invention is to provide a construction for a furnace of the type indicated attaining a high temperature in the working chamber for a given temperature in the combustion chamber. Another object of the invention is to transmit heat so that the ware chamber shall have an even distribution thereof avoiding the localization or concentration thereof in a particular spot. Other objects will be in part obvious or in part pointed out hereinafter.

The invention accordingly consists in the features of construction, combinations of elements, and arrangements of parts, all as will be illustratively described herein and the scope of the application of which will be indicated in the following claims.

In the accompanying drawing showing one of many possible embodiments of the invention.

Fig. 1 is a vertical cross sectional view through a Manion type furnace equipped with muffle plates according to the invention;

Fig. 2 is a plan view of a plate or tile;

Fig. 3 is a cross sectional view on the line 3—3 of Fig. 2;

Fig. 4 is a cross sectional view on the line 4—4 of Fig. 2;

Figs. 5 and 6 are end elevations of the plate or tile of Fig. 2;

Fig. 7 is an enlarged cross sectional view showing the manner in which adjacent plates or tiles are joined together at the apexes of the bottom structure.

The Manion type of furnace is described in United States Letters Patent No. 1,607,681 aforesaid. While so far as certain features of the invention are concerned the plate or tile which is more specifically the subject matter of my invention is adapted for incorporation into such a furnace, it must be understood that it may also

be used in other furnaces. In Fig. 1 I have shown so much of the Manion furnace as contributes to an understanding of the present invention. Referring to Fig. 1, there is provided a bottom wall 10 and side walls 11, 11. There are also provided spaced piles or piers 12 projecting from each side wall and in parallel relation, individual piles or piers on either side being opposite each other. Between the piles or piers 12 are additional piles or piers 13, 13 also in parallel evenly spaced relation, with individual piles or piers opposite each other and also opposite corresponding piles or piers 12. The piles or piers 12 and 13 taken all together define bottom combustion chambers 14 and which communicate with upwardly extending side combustion chambers 15. The furnace provides a ware chamber 16 which is separated from the side combustion chambers 15 by means of refractory side walls 17, 17 spaced from the main side walls 11 and comprising interlocked refractory plates or tiles 18 the bottom rows of which rest upon the piers 12. The ware chamber 16 is separated from the combustion chambers 14 by means of a refractory V bottom construction which as a whole and the individual tile members of which more particularly constitute the subject matter of the present invention.

Referring now to Fig. 2, I provide a plurality of identical tiles or plates 20 together with a plurality of similar but oppositely oriented tiles or plates 20a all of which will be understood from the following description of the plate 20. The plate 20 may be made of any suitable refractory material, but I prefer to construct it of highly refractory granular material bonded together with a refractory vitrified bond. Specifically I may use refractory grain of the material aluminum oxide or of the material silicon carbide or, for example, magnesium oxide or any other suitable refractory material. The bond may be a ceramic bond of high refractory qualities or any other suitable type, for example, self-bonded granular material may be employed and also the improved plates might be directly cast from a molten refractory.

Considering now the structure of the plates 20, and referring to all of Figs. 2, 3, 4, 5, and 6, each plate has a top surface having a plurality, for example three, grooves 21 therein. Each plate 20 has a bottom surface having a plurality, for example two, grooves 22 therein. The grooves 21 and 22 are all parallel to each other and evenly spaced so that the wall portion 23 between them is substantially of the same thickness between the opposite edges of the outermost grooves 22. From that point outward on each side, however,

the material gradually increases in thickness to the ends 24 and 25; the end 24 being in this illustrative embodiment of the invention a grooved end, and the end 25 having a dovetail as shown.

5 One end 26 of each plate 20 is mitered forming dihedral angles with the top and bottom of the plate 20 of approximately 45° and forming a mitered edge of approximately 90°. The other end of each plate 20 is divided into two equal 10 parts; one of these comprises a dovetailed end 30, and the other comprises a grooved end 31 having a groove 32 that is oriented in an angular position 90° from that of the dovetailed end 30. This relationship will be more readily apparent 15 from a comparison of Figs. 2 and 6 and by reference also to Figs. 4 and 5.

The plates 20 are each of them joined with corresponding but oppositely oriented plates 20a to form the structure shown in Fig. 1, in which 20 pairs of plates are joined together with each groove 32 of one plate resting on top of the dovetail or tongue 30 of another plate. At one 25 end of each pair of plates 20 and 20a are dovetails or tongues 25 while the other end of each pair of plates 20 and 20a are grooved ends 24. However, variations in the positions of tongues and grooves may be made, for example a particular end of a plate 20 might have a tongue 30 while the end of the plate 20a in the same plane might have a groove, i. e. plates 20 can be interlocked.

In assembling the plates in the furnace, a pair of plates 20 and 20a may be interlocked together and pushed into position in a line which is normal to the view in Fig. 1.

With the plates arranged as described, there are three grooves 21 on the upper side of each plate and a pair of grooves 22 on the lower side of each plate. Nevertheless because the plates 40 are of full thickness all along each of the four ends thereof, each plate is substantially as strong as it would be were it of the same outline but solid. On the other hand, however, because the cross section for heat transference is very much 45 less, a great deal more heat is conducted through each plate than is conducted through a solid of the same outline. Furthermore, because of the broken upper surface of each plate heat diffusion is better achieved. I desire to avoid a concentration of heat at any one particular spot and I have found that a corrugated upper surface avoids such concentration.

Considering now the resistance of my plates to a load thereon, by reason of the fact that there are two central ridges 35, 35 as well as the thick portions 36 and 37 on the upper side of each plate, they are substantially as strong as they 5 would be if solid. That is to say, removal of material in the manner described has, from a practical standpoint, reduced the strength of each plate to resist a load on top of the apexes 40 to a substantially immaterial extent. The plates can 10 be assembled in a furnace in a very short time and the ends 26 abut against each other and against the walls 18 and hold the individual plates together to form a V bottom to the ware chamber and a V top to the combustion chambers 14. 15 At the same time the joints may be made quite tight so that the gases of combustion will not reach the air chamber. Such slight openings as remain after the plates are pushed together are readily closed with cement. But because of the 20 interlocking arrangement there is little tendency of the gases to burn through the cement.

It will thus be seen that there has been provided by this invention a muffle plate in which the various objects hereinbefore set forth together with many thoroughly practical advantages are successfully achieved. As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

I claim:

35 A pair of muffle plates for a V bottom muffle furnace, each plate being substantially rectangular and having depressions in its opposite sides in the form of parallel grooves staggered so as to make the plate corrugated in cross section with 40 marginal portions of a thickness the same as the greatest amplitude of the corrugations, and along one marginal wall of each plate there being for part of the distance a tongue portion and for the remainder of the distance a groove portion, 45 said tongue portion and said groove portion extending from planes of the margin at 90° to each other, whereby the plates may be interlocked together to add strength.

50 ROBERT KIRKPATRICK.
